G. E. DOUGHTY

HAT TREE

Filed Jan. 17, 1922

UNITED STATES PATENT OFFICE.

GEORGE E. DOUGHTY, OF NEW YORK, N. Y.

HAT TREE.

Application filed January 17, 1922. Serial No. 529,870.

To all whom it may concern:

Be it known that I, GEORGE E. DOUGHTY, a citizen of the United States, and a resident of the borough of Manhattan, city, 5 county, and State of New York, have invented a certain new and useful Hat Tree, of which the following is a specification.

My invention relates to a device adapted to be placed in a hat to preserve the latter 10 in shape when not being worn, and has for its objects to provide such a device which is capable of being adjusted to fit and engage the sweat band in a hat having a head opening of any configuration, which 15 will be light in construction whereby its weight will not affect the shape of any part of the hat; which will be cheap of manufacture; which will not get out of order, and which may be adjusted without the use 20 of tools.

These and further objects will more fully appear in the following specification and accompanying drawing considered together or separately.

25 Stiff hats such as derbies, silk hats and straw hats, are usually fitted to conform to the shape of the head of the wearer, and as long as they are worn day after day may retain the shape. When the hat is laid 30 aside for a more or less considerable period of time it will warp out of shape owing to the drying out of moisture, or to other causes, and such warping will not only destroy the contour of the head opening but 35 will warp the brim, particularly in straw hats, out of shape, and render the hat worthless.

By applying the device of my invention 40 to the hat and in engagement with the sweat band, the device will engage the entire circumference of the head opening and prevent any change in the contour thereof.

With the device in place the hat need 45 not be stored away resting on its brim, but it may be hung on a hook or the like, whereby economy of space will be secured.

I have illustrated one embodiment of my 50 invention in the accompanying drawings, in which like parts in all of the several figures, are designated by corresponding characters in reference, and in which

Fig. 1 is a plan view of the device.

Fig. 2 is a side elevation of the same.

Fig. 3 is a section on the line 3, 3 of Fig. 1. 55

Fig. 4 is a section on the line 4, 4 of Fig. 1.

Fig. 5 is a section on the line 5, 5 of Fig. 1.

Fig. 6 is a section on the line 6, 6 of Fig. 5, and 60

Fig. 7 is a section on the line 7, 7 of Fig. 5.

The device comprises a practically endless band formed on two arch-shaped members 65 8 and 9 each formed of a curved strip of thin, flexible material, such as metal, celluloid or the like. The free ends of the members overlap as shown, and the overlapping ends of the member 9 are in engagement with the inner side of the member 7 as shown, whereby a more or less oval band is produced.

The free ends of the member 9 are each provided with an elongated slot 10 extending longitudinally thereof, and the inner end of each slot is provided with an enlargement 11, as shown. 75

Secured to the center of the inner side of the arch of the member 9, by riveting or otherwise, is a bar 12 of preferably rectangular cross-section extending longitudinally of the band, the extremity of the bar opposite the secured end being free. A similar bar 13 is secured to the member 8 in alignment with 80 the bar 12 and rests upon said latter bar. The bars 12 and 13 pass through openings 20 in the sides of a trough-shaped fitting 14.

Secured to the member 8 and extending 90 at right angles to the bars 12 and 13 are two similar but shorter bars 15 and 16 each of which is riveted to the member 8 and extend inward in opposite directions, one resting on the other. Each of the bars 95 15 and 16 extends through a slot 10 near its point of attachment to the member 8, and both of said bars pass through the fitting 14 between the base thereof and the bars 12 and 13. 100

A screw 17 threaded into the base of the fitting engages the bar 15 and is provided with a wing head 18 whereby the same may be rotated to clamp the bars 12, 13, 15 and 16 together and in the fitting 14 at the 105 point of crossing of the bars.

A portion 19 of each end of the member 8 is struck up therefrom and inward and projects through each slot 10. The portions 19 are wider than the slots and overlap the edges thereof whereby the sides of the member 8 are held in contact with the sides of the member 9, and movements of the members toward and away from each other in the direction longitudinally of the band 10 are permitted by movement of the portions 19 longitudinally of the slots.

When the members 8 and 9 are assembled to form the band, the free ends of the member 9 are placed against and inside of the free ends of the member 8, and the members are slid towards each other until each portion 19 is opposite an enlargement 11. The portions 19 will enter the enlargements 11, and when the arch-shaped members are 20 moved longitudinally away from each other the portions 19 will engage the walls of the member 9 at the sides of the slots 10 and prevent the adjoining ends of the members from springing apart.

25 In operation the screw 17 is backed out a short distance, and the bars 12, 13, 15 and 16 are released from rigid engagement with each other and with the fitting 14. The members 8 and 9 are separated longitudinally 30 until the center of the arch of the member 9 engages the front of the head opening of the hat, and the center of the arch formed by the member 9 engages the point at the diametrically opposite side of 35 the head opening, the bars 12 and 13 sliding in the openings 20 in the sides of the fitting 14, and the portions 19 sliding in the slots 10, 10. The rods 15 and 16 are then moved apart until the sides of the band engage the 40 sides of the head opening.

The rod 13 is pulled through the fitting to a greater extent than is the rod 12 whereby the arch crown of the band member 8 will be further from the cross rods 15 and 45 16 than is the crown of the member 9, and these latter rods will extend across the band at the widest portion of the head opening. By varying the distance to which each rod is withdrawn from the fitting, 14, the band, 50 as a whole, may be made to conform to the exact shape of any hat. When the band is in contact with all points within the head opening, the screw 17 is tightened, the bars 12, 13, 15 and 16 are securely clamped together and to the fitting 14, and the hat 55 will be prevented from changing its shape because of heat, moisture or for any other reason.

60 In accordance with the provisions of the patent statutes the principle of the invention has been described, together with the apparatus which is now considered to represent the best embodiment thereof, but it is desired to have it understood that the apparatus shown is merely illustrative, and that

the invention may be carried out in other ways.

The invention having been described, what is claimed and desired to be secured by Letters Patent, is

70 1. A device of the character described, comprising an endless band formed of a pair of opposed flexible, arched members, the open end of one member engaging within the open end of the other member, means for preventing separation of the members, said means permitting movement of the members toward and away from each other, a frame comprising two elements crossing each other at right angles and resting one 75 upon the other, the ends of the elements being secured to the band, means for varying the lengths of the elements, and means engaging the elements one with the other for securing the same together.

80 2. A device of the character described, comprising an endless band formed of a pair of opposed, flexible, arched members, the open end of one member engaging within the open end of the other member, means 85 for preventing separation of the members, said means permitting movement of the members toward and away from each other, a frame comprising two elements crossing each other at right angles and resting one upon the other, the ends of the elements being secured to the band, means for varying the lengths of the elements, each element comprising two bars resting one upon the other, one end of each bar being free of the 90 band, and means for clamping all of the bars together at the point of intersection of the elements.

95 3. A device of the character described, comprising an endless band formed of a pair of opposed, flexible, arched members, the open end of one member engaging within the open end of the other member, means 100 for preventing separation of the members, said means permitting movement of the members toward and away from each other, a frame comprising two elements crossing each other at right angles and resting one 105 upon the other, the ends of the elements being secured to the band, means for varying the lengths of the elements, each element comprising two bars resting one upon the other, one end of each bar being free of the 110 band, a fitting enclosing the elements at the intersection thereof, said elements 115 passing freely through the fitting, and means for clamping all of the bars together and to the fitting at the point of intersection of the elements.

120 4. A device of the character described, comprising an endless band formed of a pair of opposed, flexible arched members, the open end of one member engaging with the open end of the other member, means 125 for preventing separation of the members, 130

said means permitting movement of the members toward and away from each other, a frame comprising two elements crossing each other at right angles and resting one upon the other the ends of the elements being secured to the band, means for varying the lengths of the elements, each element comprising two bars resting one upon the other, one end of each bar being free 10 of the band, a fitting enclosing the elements at the intersection thereof, said elements passing freely through the fitting, and a screw for clamping all of the bars together and to the fitting at the point of 15 intersection of the elements.

5. A device of the character described, comprising an endless band composed of two opposed arch shaped members of flexible material, the sides of one member fitting within and engaging the sides of the second member, there being an elongated slot in each side of the first mentioned member, means integral with the second member and passing through the slots to prevent 50 separation of the members, a bar secured in the crown of each member and extending toward the crown of the other member, one end of each bar being free, said bars being parallel and resting one upon the other for 55 a portion at least of their length, a bar secured to each side of the second member and extending inwardly through the slots in the first member, one end of each of said last mentioned bars being free and said bars resting one upon the other for a portion at least of their length, said bars crossing the first mentioned bars at right angles, a fitting having right angle passages 60 therethrough, the first mentioned bars passing through one passage, the second mentioned bars passing through the other passage at the intersecting point, said passages being in communication and a single screw for 65 securing all of the bars together and to the 70 fitting at the point of intersection of the bars.

This specification signed and witnessed this fourteenth day of January, 1922.

GEORGE E. DOUGHTY.
